UNITED STATES PATENT OFFICE.

ROGER S. WHITE, OF WASHINGTON, DISTRICT OF COLUMBIA.

ELECTRIC METER.

Application filed July 5, 1924. Serial No. 724,533.

To all whom it may concern:

Be it known that I, ROGER S. WHITE, a citizen of the United States, residing at Washington, in the District of Columbia, 5 have invented certain new and useful Improvements in Electric Meters, of which the following is a specification.

This invention relates to improvements in a well known type of direct current watt-hour meter, known generally as the Sangamo meter. In these meters, the motor element comprises a disk armature which rotates in a chamber filled with mercury, and a damping disk is mounted upon the 10 top of the chamber and connected to the armature shaft. The chamber is composed of a hollow block of insulating material, to the bottom of which is secured a metal pan for supporting the mercury. These 15 parts, with the recording train, are assembled as a unit, and are secured by screws to a ring-shaped supporting bracket which is fastened to the back wall of the meter housing. The magnet of the motor is separately 20 supported in the housing, and the pole pieces of the magnet project into the space enclosed by the ring and close to the underside of the mercury pan. The construction is such that the motor element cannot be 25 removed for inspection of the mercury chamber without removing the magnet and the supporting bracket to which the motor element is secured and without undoing certain electrical and mechanical connections, 30 all of which amounts substantially to dismantling the meter.

In mercury meters, the oxide forming on the surface of the mercury sometimes clogs and retards the motor, and when that occurs it is necessary to remove the motor element and inspect and clean the mercury chamber. This operation, with the standard meters of the type referred to requires considerable time, a large part of which is 45 occupied in removing the parts from the meter casing and replacing the same, and in undoing and re-establishing the necessary electrical connections.

In the present invention, I have made certain changes in and additions to the structure of meters of the type referred to, whereby the motor element may be quickly removed or replaced in the meter casing without removing the supporting bracket or the magnet, or disturbing the electrical connections of the magnet, and whereby other elec-

trical connections can be broken or established with greater facility than in the meters as at present constructed.

In the accompanying drawing, 60

Fig. 1 is a front perspective view of a mercury meter, with the front of the casing, the recording train and other parts removed, showing my improvements;

Fig. 2 is a similar view, showing the motor 65 element removed from the casing;

Fig. 3 is a perspective view of the parts composing the mercury chamber, said parts being separated from one another;

Fig. 4 is a central, vertical section through 70 the assembled motor element;

Fig. 5 is a perspective view of the main supporting bracket with the insulating binding posts thereon;

Fig. 6 is a detail perspective view showing the supporting bracket, a part of the motor element, and the electrical connections to the motor element as embodied in the meters heretofore in use; and,

Fig. 6^a is a perspective view, on a smaller 80 scale, of the bracket heretofore in use.

Referring to Figs. 1 to 5, inclusive, of the drawing, *a* represents the rear part of the meter casing, in the upper part of which are arranged the permanent magnets 1, between 85 the poles of which the damping disk 2 revolves, and in the lower part of the casing, and secured thereto by a screw 3, is the electromagnet 4 which forms a part of the motor of the meter. A main supporting bracket 5 is secured to the back of the meter casing by screws 6, and this bracket supports the motor element, indicated as a whole by the letter *b*. This motor element comprises a hollow block of insulating material 7, 95 closed at the bottom by a metal pan 8, which, in Fig. 4, is held in place against the insulating material by a clamping ring 9. In the standard form of this type of meter, the pan 8^a is secured by screws to the bottom of the 100 insulation and rests directly upon the bracket 5, as shown in Fig. 6, the horizontal part of the bracket being in the form of a ring. The chamber enclosed by the hollow block 7 and pan 8 contains mercury, indicated at 11, and the armature 12 of the motor is rotatable in the mercury. The armature shaft 13 extends upwardly above the mercury chamber and carries the damping disk 2 and a worm 14, the latter for driving the registering train, not shown. The structure shown in Fig. 4 of the drawing is the same

105
110

as the standard form except for the addition of the clamping ring and a slight change in the form of the pan to make it flush with the ring, and also for a change in the form and arrangement of the ears or terminals 15, through which current is carried to and from the mercury and the armature immersed in the mercury. In the standard form of meter, these ears are flat, horizontally arranged lugs, as indicated at 15^a in Fig. 6, and these lugs are provided with vertical openings through which studs 16 pass, and the terminals 17 of the series coil of the motor magnet and the flat bands 18, which 10 lead to and support the light load adjusting means, are clamped to the terminals 15^a by the studs 16. According to my improvements, as shown in Fig. 4, the ears or terminals 15 have horizontal openings 19, in which are fitted tubes 20, (Figs. 1, 2, and 3) 15 which are adapted to pass on to studs or binding posts 21 which are supported by blocks of insulating material 22, which are secured to the top of the bracket 5. The terminals 17 of the 20 series coil of the motor magnet also, in accordance with my improvements, fit over the studs 21 and against the insulating blocks 22, and when the motor element is in position upon the bracket, the tubes 20 bear 25 against these terminals. The bands 18, which support the light load adjusting means, are also formed and perforated so as to fit on to the binding posts 21 and against the outer ends of the tubes 20, and clamping nuts 23, threaded on to the ends of the binding posts, clamp the several parts of the 30 posts together.

In the meters of this type as ordinarily constructed, the horizontal portion of the 40 bracket 5^a is in the form of a ring and the motor element is securely fastened to this ring by a number of screws 24, (Fig. 6) spaced suitable distances apart about the ring. These screws pass through the flange 45 7^a of the mercury chamber. With this construction, in the meters of standard make, it is impossible to remove the motor element without removing the bracket. Also, in the standard form of meter, the magnet poles 50 project into the space enclosed by the ring on the shelf and are interlocked with the shelf, so that it is impossible to remove the shelf and motor element without also removing the motor magnet after undoing its electrical connections.

According to my improvements, it is unnecessary to secure the motor element to the bracket or shelf by screws, because the studs 60 21, passing through the tubes of the terminals 15, hold the motor element in its proper position over the magnet and the motor element therefore simply rests upon the shelf without being directly secured thereto. Preferably, although not necessarily, the front half of the ring of the bracket or shelf is

removed, leaving only a semi-circular part, as shown in Figs. 1, 2, 3, and 5.

With this modified construction of the standard form of meter, it will be evident that the motor element may be removed in a few moments by loosening the nuts 23 and sliding the motor element forward on the rods 21. As will be plain from Fig. 2, the motor magnet and its connections are not disturbed by removing the motor element. It will also be evident that the motor element can be replaced in its proper position and the connections made by sliding the element backward on the shelf and causing the tubes on the armature terminals to pass on to the rods 21. When the bands 18 are applied to the front ends of the rods and the nuts are tightened, all of the electrical connections will be re-established and the motor element will be securely held in its proper position.

If desired, the supporting bracket may be omitted and the motor element will then be entirely supported by the rods 21, fitting within the tubes or sleeves 20. In that event, the insulating supports for the posts would, of course, be secured to the back of the casing instead of the bracket.

What I claim is:

1. In a meter of the type described, a casing, a horizontally arranged bracket secured within the casing, a motor element, having armature terminals projecting from its sides, slidably mounted on the bracket, and stationary insulated terminals adapted to be engaged by said armature terminals when the armature is on the bracket. 95

2. In a meter of the type described, a casing, a horizontally arranged bracket secured within the casing, a motor element, having armature terminals projecting from its sides, slidably mounted on the bracket, and stationary insulated binding posts adapted to be engaged by said armature terminals when the armature is on the bracket. 105

3. In a meter of the type described, a casing, a horizontally arranged bracket secured within the casing, a motor-element slidably mounted on the bracket, said element having armature terminals projecting from its sides and said terminals having horizontal openings, and stationary insulated binding posts adapted to pass into said openings when the motor-element is slid on to the shelf. 115

4. In a meter of the type described, a casing, a horizontally arranged bracket secured within the casing, a motor-element slidably mounted on the bracket, said element having armature terminals projecting from the sides and said terminals comprising horizontally arranged sleeves, and stationary insulated binding posts supported on the bracket and adapted to pass into said sleeves when the motor-element is slid on to the shelf. 125

5. In a meter of the type described, a cas- 130

ing, a horizontally arranged bracket secured therein, insulated binding posts extending horizontally adjacent the bracket, a motor element having a mercury chamber, said 5 chamber comprising a hollow member of insulating material, a metal pan fitting against the under side of said member, and a clamping ring securing said pan to said member and substantially flush with the bottom of 10 the pan, said ring adapted to slidingly engage and rest upon the bracket and said element having terminals adapted to engage

said binding posts when the element is slid on to the bracket.

6. In a meter of the type described, a casing, stationary insulated binding posts extending horizontally in said casing, and a motor element having armature terminals projecting from its sides, said terminals adapted to slidingly engage said posts. 15 20

In testimony whereof I hereunto affix my signature.

ROGER S. WHITE.
